TREATMENT OF HYDROCARBON OIL

Jean Delattre Seguy, Chicago, Ill., assignor to
 Universal Oil Products Company, Chicago, Ill.,
 a corporation of South Dakota

Application August 16, 1930, Serial No. 475,704

1 Claim. (Cl. 196—48)

This invention relates to the treatment of hydrocarbon oils, and refers more particularly to the conversion of high boiling hydrocarbons into lower boiling hydrocarbons.

5 In one specific embodiment, the invention contemplates a process for the treatment of hydrocarbon oils which comprises subjecting relatively clean oils such as reflux condensates (obtained from conversion under pressure, or from additional vaporization under reduced pressure of the residuum from the conversion zone) to cracking conditions, these reflux condensates being obtained by subjecting the raw oil to be treated in the process (with or without preliminary independent heat treatment at temperatures such that vaporization with or without cracking may take place) to direct heat exchange with the unvaporized oil from the primary reaction zone as it undergoes flash distillation. In this manner 10 the coke-forming constituents of the raw oil are removed from the process in admixture with the residuum from the so called flash chamber. The light constituents of the raw oil and those formed by its preliminary heat treatment are removed 15 with the vaporized parts of the unvaporized oil from the primary reaction zone and these vaporized constituents are then subjected to condensation to form so called flash condensate which is subjected to cracking treatment in the primary reaction zone in admixture with reflux condensate formed from the vapors evolved in said treatment in said primary reaction zone.

The utility of the invention as well as the objects and advantages thereof, will be better understood by referring to the accompanying drawing, which is a diagrammatic side elevational view of an apparatus suitable for carrying out the process of the invention.

40 The raw oil charging stock is fed through line 1, valve 2, and is pumped by pump 3 through line 4, controlled by valve 5, through indirect heat exchanger 6, line 7 and valve 8.

45 Thereafter, this preheated raw oil may be passed through line 40, valve 44, and line 14 where it mixes with the unvaporized oil from the reaction chamber 18 as will be hereafter explained, or the raw oil from line 7 may be subjected to additional heat treatment by passing through line 9 and valve 8 and thence into the heating element 10 located in furnace setting 11. In the heating element 10, depending upon the composition of the raw oil, conditions of vaporization with cracking or without cracking may be maintained. It is preferable, if the charging stock contains a substantial proportion of gaso-

line or light fractions, that vaporizing but non-cracking temperatures be reached in the heating element 10. In this alternative such pressure may be maintained in the heating element 10 that only a limited vaporization takes place, additional vaporization of the charging stock taking place upon reduction of pressure by means of valves 13 or 15 or both, and by admixture of the oil leaving heating element 10 with the residuum from chamber 18.

5 On the other hand, if the charging stock fed to the process is a residuum or topped crude, conditions in the heating element 10 may be such that a conversion temperature is reached and a condition is maintained to obtain substantial conversion of the raw oil under pressure.

Raw oil, if desired, may be fed directly to the heating element 10, if the latter is used, and without passing through preheating coil 6. This may be done by proper manipulation of valve 16 in line 19. The oil leaving the heating element 10, if the latter is used, is discharged through line 12 having valve 13 and is then passed through line 14 having valve 15 combining with the unvaporized oil from reaction chamber 18, and discharging therewith into flash chamber 17, where in vapors separate from unvaporized residue.

10 The unvaporized oil entering the flash chamber 17 is withdrawn from the reaction chamber 18 through line 21, controlled by valve 20, and passes through line 14 and valve 15 into the flash chamber 17, owing to the reduction in pressure at the valve and the latent or stored heat of the oil, a substantial portion of the residue leaving the reaction chamber vaporizes. The vapors 15 evolved from the flash chamber which comprise vapors from the flash chamber which comprise vapors evolved from the unvaporized oil removed from reaction chamber 18 and vapors evolved from the raw oil charging stock, pass through line 22, controlled by valve 23, into the flash dephlegmator 24 where, owing to the cooling action of the raw oil charging stock passing through the heat exchanger 6, a substantial portion thereof condenses. The flash condensate thus produced passes through line 25, valve 26, and may be 20 pumped by means of pump 27 through lines 28 and 29 and valve 30, into the primary dephlegmator 31, where it meets the ascending vapors from the reaction chamber 18 and causes a partial condensation of the heavier components 25 thereof. The combined flash condensate and reflux condensate from the primary dephlegmator 31 passes through line 32, controlled by valve 33, and is pumped by means of pump 34 through line 35 into the heating element 36 located in 30

furnace setting 37. Flash condensate from dephlegmator 24 may by-pass dephlegmator 31 in any desired proportion, being directly supplied to pump 34 through valve 19 in line 28. The combined reflux and flash condensates are raised to conversion temperature in the heating element 36 and pass through transfer line 39, controlled by valve 38, into reaction chamber 18. The vapors leaving the reaction chamber 18 pass through line 41, controlled by valve 42, into dephlegmator 31, where the afore-mentioned heat interchange occurs, causing the condensation of the heavier components of the vapors entering dephlegmator 31. Additional cooling is accomplished by the introduction into the dephlegmator 31 of some of the low boiling products of the process. The vapors leaving dephlegmator 31 pass through line 43 controlled by valve 45, into cooler and condenser 46, through line 47, controlled by valve 48, into receiver 49. The liquid distillate of the process is withdrawn through line 50, controlled by valve 51. The gases of the process are withdrawn through line 52, controlled by valve 53, which also serves as the pressure control valve upon the receiver.

The unvaporized residue referred to as flashed residuum which contains unvaporized heavy portions of the raw oil charging stock is withdrawn from the flash chamber 17 through line 54, controlled by valve 55. The vapors leaving the flash dephlegmator 24 pass through line 57, controlled by valve 58, through cooler and condenser 59, controlled by valve 60, and through line 61 into receiver 62. The liquid product which accumulates in receiver 62 is withdrawn through line 63, controlled by valve 64. Any vapors or gases accumulating in the receiver 62 are withdrawn through line 65, controlled by valve 66. A portion of the final low boiling product of the process from receiver 49 may be withdrawn through line 67, controlled by valve 68, and pumped by means of pump 69 through line 72 and valve 73, into the primary dephlegmator 31 for the purpose of cooling the vapors arising therein and permitting control of the separation of the lower boiling components from the heavier boiling components.

The operating conditions of the process may be varied over a wide range, the temperature in the heating element 36 being preferably well within the cracking range, and preferably higher than that in the heating coil 10. I may maintain the so called vapor-phase conditions of cracking or high temperature heating within the heating coil 35.

As stated, when the charging stock does contain any fractions of the character of light distillates such as gasoline or naphtha, the temperature in the heating coil 10, may be sufficient to promote vaporization with no or little conversion or it may be such that under the conditions of operation substantial conversion takes place before the stock enters the chamber 17. When the charging stock contains gasoline or like fractions, then it is preferable that the temperature in the heating coil 10, if the latter is used, be one where no or only little conversion takes place, providing principally for the fractional distillation of the crude oil.

The pressures on the system may vary from sub-atmospheric to high super-atmospheric, preferably maintaining a substantially super-atmospheric pressure upon the heating elements and the reaction chamber with either equalized or lowered pressure upon the remainder of the sys-

tem, but in all cases maintaining a substantially lower pressure upon the flash chamber and elements succeeding it.

With some conditions of operation, particularly when simple distillation with little or no cracking is to take place on the raw oil, I may maintain a pressure on heating element 10 only slightly higher than that on flash chamber 17.

As a specific example of the operating conditions and yields of products obtained by the operation of the process of my invention, a 30 degree A. P. I. gravity topped crude oil was charged to the process. A pressure of approximately 150 pounds per square inch and a temperature of approximately 910° F. was maintained upon the heating element 10.

A temperature of approximately 950° F. and a pressure of approximately 200 pounds per square inch was maintained upon the heating element 36, and the pressure upon the reaction chamber 18 was approximately 200 pounds per square inch. The pressures upon the primary dephlegmator 31, condenser 46 and receiver 49 were substantially equalized with respect to that upon the reaction chamber 18, showing some drop resulting from frictional resistance to flow through the system.

The pressures upon the flash chamber 17, flash dephlegmator 24, flash condenser 59 and receiver 62 were substantially equalized, the pressure upon the flash chamber 17 being approximately 35 pounds per square inch.

A yield of approximately 65% of pressure distillate composed of 50% gasoline and 15% pressure distillate bottoms, all based on the raw oil charged to the system, was obtained. A yield of approximately 30% of flashed residuum containing less than 2% of suspended carbonaceous or pitchy matter and having a viscosity and gravity suitable for fuel was produced at the same time. The yield of gas was approximately 450 cubic feet per barrel of raw oil charged, and a small amount of carbon or coke was produced. Increasing the temperature on the heating element 36 increased the anti-knock value of the gasoline. In some cases, this varied over a range of 15% benzol equivalent as a function of increase in temperature on the heating element 36. For example, with a temperature of 925° F. on the heating element 36, the benzol equivalent of the gasoline was approximately 45%, while at a temperature of 970° F., the benzol was approximately 65%.

As another illustration of a manner in which the invention of the process may be carried out when using a crude oil charging stock through the process, a 35 gravity crude oil containing approximately 13% of gasoline was charged to the process and passed through the heating coil 10 under a pressure of approximately 100 pounds and it was there raised to a temperature of approximately 700° F. The pressure upon the flash chamber 17 was in the neighborhood of 30 pounds per square inch and the condensate found therein and formed in the dephlegmator 31 was treated in the heating coil 36 where it was heated to approximately 930° F. under a pressure of approximately 225 pounds per square inch, the pressure on the reaction chamber 18 being equalized with that at the discharge of the heating coil 36. In this operation a yield of approximately 75% of pressure distillate was recovered which comprised 63% gasoline and 12% of pressure distillate bottoms, these percentages being based on the crude oil charged to the system. This gasoline and pressure distillate comprised the gasoline contained originally in the crude and recovered in the 71

5 flash receiver 62. Marketable fuel oil was produced concurrently to the extent of about 20% of the crude oil charged to the process. The gasoline resulting from a mixing of the pressure distillate recovered in the receiver 49 and of the distillate recovered in the receiver 62, which amount has heretofore been stated, approximately 62% of the crude oil, had a benzol equivalent of approximately 40%.

10 10 The examples show the results obtainable under one set of conditions, and are intended to serve only as illustrations.

I claim as my invention:

15 15 A hydrocarbon oil cracking process which comprises passing relatively clean hydrocarbon distillate in a restricted stream thru a heating zone and heating the same therein to cracking temperature under sufficient pressure to maintain a substantial portion thereof in liquid phase, dis-
20 20 charging the heated oil into a vapor separating zone maintained under cracking conditions of temperature and superatmospheric pressure and separating the same therein into vapors and un-
vaporized oil, removing the separated vapors and
25 25 dephlegmating the same under superatmospheric pressure to condense insufficiently cracked fractions thereof as reflux condensate, separately re-
moving the unvaporized oil from the separating zone and flash distilling the same in a flashing

5 zone by pressure reduction, simultaneously with the foregoing operation independently heating fresh charging oil for the process, under a pressure higher than that prevailing in the flashing zone and without substantial cracking thereof, to a temperature adequate to distill a substantial portion thereof under the pressure of the flashing zone, introducing the thus heated charging oil, prior to any substantial cracking thereof, to the flashing zone and vaporizing a substantial portion thereof in the flashing zone, removing the admixed flashed vapors and charging oil vapors from the flashing zone, separately removing residuum from the flashing zone and isolating the same from the process, dephlegmating the ad- 15
10 10 mixed vapors removed from the flashing zone independently of the vapors removed from the separating zone and under the reduced pressure of the flashing zone to condense heavier fractions thereof by passing the same in indirect heat ex- 20
20 20 change relation with said charging oil undergoing heating whereby the heat of the vapors is utilized to supply at least a portion of the heat required to distill the charging oil, and supplying such con-
25 25 densing heavier fractions and said reflux condensate to the heating zone to constitute said relatively clean distillate.
